UNITED STATES PATENT OFFICE.

FRANK J. W. WEISER, OF ELMHURST, ILLINOIS.

PHONOGRAPH-HORN.

1,286,459.

Specification of Letters Patent.

Patented Dec. 3, 1918.

Application filed May 24, 1918. Serial No. 236,266.

To all whom it may concern:

Be it known that I, FRANK J. W. WEISER, a citizen of the United States, residing at Elmhurst, in the county of DuPage and State of Illinois, have invented certain new and useful Improvements in Phonograph-Horns, of which the following is a specification, reference being had therein to the accompanying drawing.

10 My invention relates to phonograph horns, and its object is to provide a sound-control to eliminate the metallic character of the tone of the sound-waves issuing from the throat of the phonograph and to control the volume of sound of the waves. The invention consists in the matters hereinafter described and then pointed out in the claims.

15 In the accompanying drawings, Figure 1 is a side view of a phonograph with the horn in vertical section to better illustrate the features of my invention; Fig. 2 is a top view in longitudinal section on the line 2—2 of Fig. 1 through the horn and showing the closed and opened positions of the shutters in full and dotted lines respectively, Fig. 3 is a sectional view on the line 3—3 of Fig. 2, and Fig. 4 is modification.

20 In the drawings the reference numeral 5 indicates the frame of a phonograph having the usual turn-table shaft 6 for the revolving record, 7 the stylus or needle-arm and 8 the sound-box carried on the hollow tone-arm 9 which is supported in the customary manner on the frame at 10 and communicates 25 with the hollow throat 11 of the horn 12. The upper and lower sounding-boards 13 and 14 respectively of the horn are flared laterally to provide a wide mouth and the upper sounding-board is also flared upwardly to enlarge the mouth, their outer corners being connected by suitable uprights 15. Each side of the horn is composed of a 30 set of pivoted wooden shutters 16 which are of substantially the same width but are of increasing length from the inner end of the horn toward its mouth as shown in Fig. 1. Each shutter is pivotally mounted at the top and bottom of its inner end by pins 17 which 35 turn in supporting strips 18 and 19 secured on the inner faces of the side edges of the sounding-boards 13 and 14 respectively, the pins having felt-bushings 20 to prevent any noise or rattle. The outer or free end of each shutter, except the outer pair at the 40 mouth, overlaps the pivoted end of the adjacent shutter when the shutters are closed

45 or collapsed, and each is provided with a sound-deadening strip of felt 21, and when the shutters are turned inwardly on their pivots they extend more or less into the area 50 of the horn. Any suitable number of shutters may be thus provided on each side of the horn though in practice I prefer to use eight on each side, with the shortest shutters adjacent the throat-opening and the succeeding ones increasing in length toward the mouth of the horn, the width of the shutters being such that when they are turned inwardly to their extended position the shortest pair with their felt-strips will be closed 55 and stand across the throat opening, and the openings between succeeding pairs will increase in width toward the mouth of the horn as shown in Figs. 2 and 3. Each shutter increases in length at its top from its 60 inner pivoted end toward its free end as shown clearly in Fig. 1, this upward slant or bevel corresponding to the upward flare of the top sounding-board so that when the shutters of each set or bank stand in their 65 full-line position in Fig. 2 they close the sides of the horn as shown in Fig. 1, the top-strip 18 being slightly thicker than the difference between the lengths of the pivoted 70 and free ends of the shutters to allow the 75 tops of the latter to clear the top sounding-board when they are turned inwardly.

80 Each set of shutters on each side of the horn is provided with an operating bar 22 which is pivotally connected at 23 to the 85 free end of an arm 24 rigidly fixed to each shutter of its set, and each bar 22 is connected at its inner end to the throat-piece 90 by a spring 25 which normally retracts the bar to maintain the shutters in their closed or collapsed position as shown in full lines 95 in Fig. 2. The bars may be operated against the tension or force of their springs to more or less open or extend the shutters inwardly 100 across the horn by any suitable means, and for this purpose I prefer to use a pull-cord 105 26 secured at its ends to the bars and which may be long enough to project to any convenient point, so that an operator may be at any distance from the machine and control the opening and closing of either or both sets of shutters. The springs normally 110 actuate each bar to close or collapse its associated set of shutters to form the closed sides of the horn as shown in full lines in Fig. 2 and afford an unobstructed area or passage of the same cross-sectional extent

as if the sides were of ordinary solid construction, and when desired the operator may partly or wholly open or expand either or both sets of shutters by moving them inwardly more or less so they will correspondingly break the sound waves flowing out of the throat and thus control the volume of the sound or tone without choking it entirely. Also by thus breaking up the sound waves when they are expanded more or less the shutters eliminate the metallic and harsh sound or tone that usually characterizes instruments of this kind, this function being aided by the felt strips. By having the shutters of gradually increasing length on each side they are made as a scale of music, and by having eight shutters in each set or bank the scale corresponds to an eight note scale.

The shutters may be varied in number and in form. For example, a variation in form is shown in Fig. 4 where each shutter comprises an inner leaf 16^a and an outer leaf 16^b, each provided with a deadening-strip 21; when the shutters stand with their outer leaves projected outwardly their inner leaves overlap and form closed sides as shown, and when the shutters are moved in the direction of the arrow their inner leaves project into the area of the horn and their outer leaves overlap and form closed sides.

I claim:

1. A horn for phonographs and like in-

struments having an upper and lower sound-board providing a flaring mouth and provided at each side with a set of shutters 35 pivotally mounted on the sound-boards and arranged in opposite pairs, the shutters being of substantially equal width and increasing in length from the innermost pair to the outermost pair, deadening-strips on 40 the free edges of the shutters, an operating-bar connected to each set of shutters, and a spring normally actuating each bar to collapse or close its associated set of shutters.

2. A horn for phonographs and like instruments having upper and lower sound-boards providing a laterally and upwardly flared mouth, a supporting-strip on each edge of the upper board, a set of shutters pivotally mounted in each strip and in the 50 lower board and arranged in opposite pairs, the shutters increasing in length from the inner pair to the outer pair and having their tops beveled from their inner ends to their outer ends to a width corresponding with 55 the thickness of said supporting strip, and means for operating each set of shutters.

In testimony whereof I affix my signature in presence of two witnesses.

FRANK J. W. WEISER.

Witnesses:

JOHN JOHNSON,
J. McROBERTS,
